(57) CLAIM

The ornamental design for a helmet, as shown and described.

DESCRIPTION

FIG. 1 is a perspective view of a helmet, showing our new design;
FIG. 2 is a right-side elevation view of the helmet of FIG. 1;
FIG. 3 is a left-side elevation view of the helmet of FIG. 1;
FIG. 4 is a front elevation view of the helmet of FIG. 1;
FIG. 5 is a rear elevation view of the helmet of FIG. 1;
FIG. 6 is a top plan view of the helmet of FIG. 1; and,
FIG. 7 is a bottom plan view of the helmet of FIG. 1.
The environmental structure shown in broken lines forms no part of the claimed design.
